UNITED STATES PATENT OFFICE

CARL H. HANSEN, OF PORTLAND, CONNECTICUT

WINDOW SASH

Application filed January 12, 1929. Serial No. 332,107.

My invention relates to the class of devices above named, and an object of my invention, among others, is to provide a window sash that may be raised or lowered in the ordinary manner, to open or close the window, and that shall at the same time have means to provide ventilation without a direct draught through the window and which shall provide for the entrance of more or less air, as may be desired, and at the same time secure the window against intrusion.

One form of a device embodying my invention and in the construction and use of which the objects herein set out, as well as others, may be attained, is illustrated in the accompanying drawings, in which—

Figure 1 is a front view of a window sash embodying my invention.

Figure 2 is an edge view of the same.

Figure 3 is a view in section on a plane denoted by the dotted line 3—3 of Figure 1.

Figure 4 is a top view.

Figure 5 is a view in cross section on a plane denoted by the dotted line 5—5 of Figure 1.

Figure 6 is an isometric view of a fragment of the sash looking at the front and with the central portion broken out, the pane sash being partly raised.

Figure 7 is a view similar to Figure 6 but looking at the back of the sash.

My invention, in the structure illustrated and described herein, embodies a slidably mounted supporting frame, a pane sash mounted to slide in the frame and a ventilating frame secured to the supporting frame, all of these members being mounted in a window frame and jointly slidable in the same manner as is a window sash, the invention being shown herein as applied to the lower sash of the window but which may be applied as well to the upper sash.

In the accompanying drawings the numeral 8 denotes, as a whole, a supporting sash that is fitted to slide in the ways in a window frame in the same manner as is any window

sash, this frame comprising stiles 9 and a bottom rail 10. The stiles may be provided with the usual grooves 11 and recesses for receiving the cords of sash weights. The stiles 9 are provided on their inner edges with grooves 12 for the reception of the stiles of a pane sash.

This pane sash is, as to its general construction, of the same form and shape as an ordinary window sash and it has stiles 13, a bottom rail 14, a top rail 15, and a pane of glass 16. The stiles 13 are formed preferably with ribs 17 fitted to slide in the grooves 12 in the stiles 9, although the stiles of the pane sash may be formed to slide in the grooves 12 in any ordinary manner. The top rail 15 of the pane sash is formed to fit the lower rail of an upper sash, when the ventilator is applied to the lower sash, or vice versa, the bottom rail would be fitted to the top rail of a lower sash when the ventilator is applied to an upper part of the window. This fitting will be in the ordinary manner of that of the meeting rails of upper and lower sashes of windows.

This upper rail extends over the stiles 9 and is shaped to correspond therewith and especially as to a groove 18 constituting the upper part of the sash weight groove. The ventilating frame comprises stiles 19 that are rigidly secured to the stiles 9 of the supporting frame. A top rail 20 rigidly secured to the stiles 19 comprises the top of the ventilating frame, and by reason of its rigid attachment to the stiles 19, the rail 20 acts as a rigid support for the upper ends of the stiles 9 of the supporting frame.

Grooves 22 are diagonally formed in the stiles 19, and as shown in Figures 3 and 6 of the drawings, and slats 23 are located in said grooves, the upper edges of the slats extending preferably a slight distance above the bottom edge of an adjacent slat. These slats are preferably composed of glass in order not to obstruct the entrance of light through the window, these slats, by reason of their ar-

- rangement, in fact, aiding in the transmission of such light. As an aid to simplicity in construction, the bottoms of the grooves 22 may be closed by closing strips 24 secured to the sides of the stiles 19, and to permit the insertion or removal of the slats 23 retaining strips 25 are removably secured to the stiles 19, and as shown in Figure 6 of the drawings in which headed screws are passed through keyhole slots 26 in a plate 27 and through registering slots or openings in the retaining strips 25 in a manner that will be readily understood, a strip 25 being placed to permit entry of the heads of the screws through the larger part of the keyhole slot, and the strip being then moved to locate the shank of the screw in the narrower part of the keyhole slot. Said screws are secured to and project from the stiles 19.
- From this construction it will be noted that the entire sash may be raised or lowered in a manner common to the ordinary window sashes. When it is desired to have ventilation without a direct draft through the window opening, the pane sash may be raised to the required extent and the air will then pass through the opening created by raising the pane sash and through the spaces between the slats 23. The pane sash may be locked in any desired position as by means of a locking lever 28 pivotally attached to a locking lever plate 29 on the side of a stile 19, and as shown in Figure 2 of the drawings. This lever is connected with a locking or clamping bolt 30 projecting through an opening in the stile 9 to engage the face of a rib on a stile 13 within a groove 12 in the stile 9. The connection between the lever and the bolt is such that when the lever is turned the bolt is forced in or out, and when forced in, it engages the rib on the stile 13 with a clamping action.
- I claim:
1. A window sash including a supporting frame, the latter including stiles, an immovable ventilating frame rigidly secured to said supporting frame and a pane sash slidably mounted in the stiles of the supporting frame and including a top rail with its ends overlying the ends of the stiles of the supporting frame.
  2. A window sash including a supporting frame the latter including stiles, a ventilating frame rigidly secured to said supporting frame and embodying a top rail, also, by reason of its rigid connection, serving as a top rail for the stiles of the supporting frame, and a pane sash slidably mounted in the stiles of the supporting frame.
  3. A window sash including a supporting frame the latter including stiles disconnected at their upper ends, a ventilating frame rigidly secured to said supporting frame, and a pane sash recessed into and slidably mounted in the stiles of the supporting frame and

slidable upwardly beyond the ends of the stiles of the supporting frame.

4. A window sash including a supporting frame the latter including stiles disconnected at their upper ends, a ventilating frame rigidly secured to the face of said supporting frame and including a top rail serving as a support for the stiles of the supporting frame on one face thereof, and a pane sash slidably mounted in a recess in the supporting frame and above the ends of the latter and of said supporting rail.

CARL H. HANSEN.
